UNITED STATES PATENT OFFICE.

CHARLEY W. PUTNAM, OF ALLENDALE, ILLINOIS.

MONORAIL SYSTEM.

1,110,231.

Specification of Letters Patent.

Patented Sept. 8, 1914.

Application filed January 28, 1914. Serial No. 814,940.

To all whom it may concern:

Be it known that I, CHARLEY W. PUTNAM, a citizen of the United States, and a resident of Allendale, in the county of 5 Wabash and State of Illinois, have invented a new and Improved Monorail System, of which the following is a full, clear, and exact description.

This invention relates to improvements in 10 railways, and particularly to a monorail system, and has for an object to provide an improved rail support and balancing means for properly holding the car in position.

Another object of the invention is to provide 15 an improved balancing arm structure connected to the car and associated with suitable braces along the track, whereby the swaying of the car is controlled and the strain properly distributed.

A still further object of the invention is 20 to provide an adjustable track structure and a brace standard for holding the track structure in place.

In the accompanying drawings—Figure 1 25 is an end view of a car and support, the same embodying the invention, certain parts being broken away for better illustrating the structure; Fig. 2 is a transverse sectional view through one of the balancing arms, 30 fragmentary parts of surrounding members being shown in connection therewith; Fig. 3 is a detailed fragmentary sectional view through Fig. 1 approximately on line 3—3; Fig. 4 is a side view of a track, car, and 35 associated devices embodying the present invention; and Fig. 5 is a fragmentary top plan view of a monorail track and supporting means embodying the invention, the same showing cross braces for resisting side 40 vibration of the track.

Referring to the accompanying drawings by numeral 1 indicates suitable posts or uprights, and 2 indicates broadly the entire track structure (Fig. 4), which structure 45 is mounted on the posts or uprights 1. Associated with each of the posts 1 are bracing arms 3 and 4 which support suitable cables 5, 6, 7 and 8. These cables are associated with suitable balancing arms 9 and 10, 50 whereby the swaying of the car 11 will be transmitted to the cables 5 to 8, inclusive, and from thence to arms 3 and 4, which arms are of spring metal and resist said swaying. In respect to rail 24 it is to be observed 55 that the same is braced against lateral movement by bracing members 16' and also

bracing members 17' and 18', as clearly shown in Fig. 5. The bracing members 16' are connected directly with the cross members 16, while the bracing members 17' and 18' are arranged intermediate the posts, whereby a stiff, strong structure is presented for the rail 24.

The various posts or standards 1 (Fig. 1) have rigidly secured thereto cross pieces 12 60 which are braced by, and which connect suitable diverging side braces 13 and 14, and are secured to top of posts. Each of the side braces 13 and 14 is provided with a guiding groove 15. A cross member 16 is 65 mounted upon each of the posts 1 and is formed with and secured to supporting member 17 which is rounded at 18 so as to freely rock upon a support 19 rigidly secured to standard or post 1. It is to be 70 noted that each of the standards or posts 1 are bifurcated at the upper part, as shown in Fig. 3, so as to properly accommodate the respective members 17. It will be noted 75 from Fig. 3 that the member 17 is divided 80 into two parts by a dovetail joint which allows the upper section to be moved side-wise on the lower section for track alignment. A retaining bolt 21 is connected with and extends through suitable slots 22 and 23 85 in post 1 so that extra plates may be arranged on brackets 19 for raising the member 17 and consequently raising rail 24 so as to properly level or align the rail. The rail 24 is mounted upon cross member 16. 90 However, as the outer ends of member 16 only move a short distance the movement of rail 24 will be very small. The outer ends of member 16 are provided with housings 95 25 and 26 in each of which is a spring 27 designed to press against reciprocating members or plungers 28 and 29, respectively. Each of these plungers is provided with a bearing knob 30 designed to fit into the respective grooves 15 so that when member 16 is moved in either direction there will be 100 a resistance to such action, the resistance being principally created by the respective springs 27 which naturally resist such movement.

Rigidly secured to the cross member 16 105 are arms 3 and 4 which extend upwardly so that the upper end will be near the upper part of car 11, which car is provided with suitable traction wheels 31 resting on rail 24. 110 These arms support the guiding rails or cables 5, 6, 7 and 8, which guiding cables are

suitably held in place by clamps 32 and 33 bolted or otherwise secured to the arms 3 and 4. The respective arms 9 and 10 are of identical construction, and also are identically arranged in respect to the opposite sides of the car so that the description of one will equally apply to both. Referring to Fig. 2 it will be observed that arm 10 is provided with a rotatable member 34 arranged in a bearing 35 rigidly secured to car 11. An operating handle 36 is connected to member 34, and is designed to be locked either in the position shown in Fig. 2 or in several other positions, as for instance against the top of the car 15 when the arm is swung out of the way of the cables 7 and 8.

In order to hold arm 10 in any position in which it may be placed a suitable catch or pivotally mounted member 37 is arranged 20 to engage any of the notches 38 provided in handle 36. Connected with member 34 is a tubular member 39 which in turn is connected with a housing 40. The housing 40 is provided with a chamber 41 in which a 25 spring 42 is arranged, one end of spring 42 pressing against the tube 39, and the opposite end pressing against the reciprocating bar 43. The reciprocating bar 43 carries a spring catch 44 which is adapted to snap 30 into notch 45, and to act against shoulder 46 when bar 43 is moved outwardly to the position shown in Fig. 2. A cable 47 is connected with catch 44, said cable passing over a guiding pulley 48, whereby when said 35 cable is pulled catch 44 will be moved out of notch 45 and then bar 43 may be moved toward member 39 against the action of spring 42. Cable 47 is adapted to pass over suitable guiding pulleys 49 and 50 so that 40 the inner end of the cable will be interiorly of the car or arranged at any convenient point, whereby the reciprocating bar 43 may be manipulated without inconvenience. The reciprocating bar 43 is provided with a rack 45 51 which meshes with the segmental rack 52. Segmental rack 52 is journaled upon a suitable journal member 53 held in place by brackets projecting from housing 40. The lower portion of the segmental rack 52 is 55 provided with an extension 54 which acts as a journal for roller 55. The roller 55 may be held in place on extension 54 in any desired manner, and is designed to press against the rail or cable 8 while the car is moving along rail 24. A depending bar 56 is rigidly secured to housing 40, and carries a roller 57 acting in opposition to roller 55, whereby any swaying of car 11 will be transmitted either to cable 7 or to cable 8, and 60 from thence through arm 3 to the cross member 16. The movement will be also slightly transmitted from the cross member 16 to one of the springs 27, where such movement is absorbed, and arm 3 gradually springs back to its correct position.

In operation, the car 11 may be propelled by any desired means and when traveling over rail 24 will be kept properly in an upright position by the action of resilient arms 3 and 4, together with arms 9 and 10. When it is desired to switch the car to another track the cable 47 is pulled and roller 55 is moved out of engagement with rail or cable 8. After this has been done arm 10 may be swayed so as to be parallel with the car 11, if desired. It is to be noted from Fig. 4 that the track intermediate the supports is maintained in a proper position by suitable truss rods.

What I claim is—

1. In a monorail system of the class described, a plurality of posts, an adjustable track arranged on said posts, and means connected with said track for causing the swaying of the car on said track to be resiliently resisted and controlled. 80

2. In a monorail system for railways, a plurality of supporting posts, an adjustable track arranged on said posts, bracing means connected with said track for limiting the swaying movement of cars on said track, bracing members connected with each of said posts for bracing said track, and resilient means associated with said track and engaging said last mentioned bracing means for resiliently resisting any vibrating movement of said track. 90

3. In a device of the class described, a plurality of posts, a pair of diverging members mounted on each of said posts, a transverse connecting member for connecting and binding together the outer ends of said bracing members, a track structure resting on each of said posts, said track structure including a plurality of transverse braces for preventing side movement of the track, a rail arranged on said track structure for supporting a car, and bracing members connected with said cross member for bracing the car arranged on said rail. 100

4. In a device of the class described, a railway comprising a plurality of supporting posts, a cross member arranged on each of said posts, an adjustable track mounted on said posts, means for limiting the lateral vibrating movement of said track, a spring pressed plunger arranged adjacent each end of said cross member for resiliently resisting the vibration of said track, a rail arranged on said track, and bracing arms mounted on said cross member adapted to receive the swaying motion of a car arranged on said rail. 115

5. In a device of the class described, the combination with a supporting track provided with a pair of upstanding bracing members and guiding cables, of a swinging arm arranged upon a car, said swinging arm comprising a body, a pair of guiding rollers, means for shifting one of said rollers, and 125

means for locking the arm in any desired position.

6. In a device of the class described, the combination with a supporting track structure provided with car guiding members, of a car arranged on said track and a pivotally mounted guiding arm mounted on said car and adapted to engage said guiding members, said arm comprising a hollow body, a pair of rollers arranged to continually contact with said guiding members, means for continually supporting one of said rollers in a certain relationship to said body, pivotally mounted means for supporting the other of said rollers, a reciprocating member designed to move pivotally said pivotally mounted roller supporting member, means for swinging said arm from one position to the other, and a catch for locking said arm in any of its adjusted positions.

7. In a device of the class described, a plurality of supporting posts, a supporting bracket connected with each of said posts, a

supporting bar having the end resting on said bracket so as to rock thereon, a retaining pin for holding said end in place while allowing a pivotal movement, a tiltable cross member mounted on said supporting bar, a pair of spring pressed plungers arranged on said tiltable member, a bracing structure connected with said posts for engaging said spring pressed plungers, car bracing arms connected to said cross member, and means mounted on a car engaging said arms for transmitting the swaying movement of said car to said bracing member, whereby said swaying movement is resisted by said spring-steel car bracing arms.

In testimony whereof I have signed my name to this specification in the presence of two subscribing witnesses.
